UNITED STATES PATENT OFFICE.

SYDNEY DILLON, OF EDGEWOOD PARK, AND JOHN RICHARDSON, OF NORTH BRADDOCK, PENNSYLVANIA.

ENGINE-STARTING DEVICE.

No. 918,976.

Specification of Letters Patent.

Patented April 20, 1909.

Application filed September 18, 1908. Serial No. 453,633.

To all whom it may concern:

Be it known that we, SYDNEY DILLON, of Edgewood Park, Allegheny county, Pennsylvania, and JOHN RICHARDSON, of North 5 Braddock, Allegheny county, Pennsylvania, have invented a new and useful Engine-Starting Device, of which the following is a full, clear, and exact description, reference being had to the accompanying drawings, 10 forming part of this specification, in which—

Figure 1 is a longitudinal sectional side elevation of our improved apparatus applied for use in connection with a steam engine or other motor; Fig. 2 is a sectional end elevation of the same taken on the line II—II of 15 Fig. 1; Fig. 3 is a top plan view of the starting apparatus shown in Figs. 1 and 2; and Figs. 4 and 5 are detail views on a larger 20 scale showing the cross-head forming part of the apparatus.

The invention relates to apparatus employed in starting steam engines which must be moved "off center", preparatory to starting them in operation, and to motors generally, in which necessity calls for turning the motor by a step by step movement, each step moving the motor through a small part of a revolution.

The object of our invention is to provide 30 improved apparatus by the use of which such motors may be moved by such step by step movement and by which the motors may be rotated in either direction as is desired.

A further object of our invention is to provide 35 apparatus by which the motor is moved and is held in its moved position after each step by step movement of the fly wheel or pulley.

The invention consists in apparatus comprising 40 a fluid pressure cylinder having connections arranged to engage with the fly wheel or driving pulley of a motor and revolve the wheel by a step by step movement, each step moving the wheel through a part of 45 a revolution.

The invention further consists in mounting the turning dogs forming part of the apparatus so as to permit of their being used to rotate the wheel or pulley in either of opposite 50 directions and in arranging the dogs with relation to each other so that one dog will hold the wheel in its moved position until such time as the second dog engages with and starts to move the wheel in the next step of 55 the turning operation.

In the drawings, 2 represents the fly wheel or driving pulley of a steam engine or other motor, the peripheral face of this fly wheel being provided with a series of barring notches 3. Located in front of and in line 60 with the wheel is our improved starting apparatus, the frame 4 of which is securely held on a suitable foundation provided for that purpose, and secured to the frame 4 is a fluid pressure cylinder 5 which is provided with a 65 reciprocating piston 6 and piston rod 7. The cylinder 5 is provided with ports 8 and 8', these ports being connected by suitable piping with a source of fluid pressure, a hand-operated valve being placed in the 70 piping in a suitable location for operating the cylinder. Pivotaly mounted on pins or shafts 9 are the bell cranks 11 and 12, the shafts being secured in place in suitable bearings provided on the frame 4 by means 75 of the set screws 10. One arm of each of the bell cranks 11 and 12 is forked so as to embrace the sides of the cross head 13, which is keyed or otherwise secured in place on the piston rod 7 so as to be reciprocated with the 80 piston rod 7 by the piston 6. The forked ends of the bell-cranks 11 and 12 which are connected to the cross-head are provided with pins 14 and 15, these pins extending through the slots 17 and 18 in the cross head 85 13. A bearing 16 is rotatably secured on each of the pins 14 and 15 and these bearings are arranged to slide in the slots 17 and 18 provided for that purpose in the cross head 13, when the bell-cranks are actuated in 90 moving the engine. The cross-head 13 is provided with oppositely extending wings or guides 19 which reciprocate between the slides 20, the slides 20 being removably secured in the slots provided for that purpose 95 in the sides of the frame 4. The opposite arms on each of the bell-cranks 11 and 12 also are forked, and swinging dogs 21 and 22 are mounted upon pins or shafts 23 which are pivoted in the bearings provided on the 100 arms 11 and 12. The dogs 21 and 22 each have projecting fingers 24, 24^a, 25 and 25^a, which are arranged to engage in the barring notches 3 on the fly wheel and move the fly wheel when the apparatus is actuated. The 105 dogs 21 and 22 are each provided with a counterweight 26 by which these dogs are yieldingly held in contact with the face of the fly wheel, the counterweights being mounted on counterweight arms 27 which 110

are located angularly with regard to the dogs 21 and 22 so as to hold the dogs in contact with the face of the fly wheel when the wheel is being moved by the other of the dogs, and 5 hand turning levers 30 are provided for turning the dogs 21 and 22 and shafts 23 into and out of their operative positions.

When the engine or other motor is being driven to operate the mechanism with which 10 it is connected, the dogs 21 and 22 are held in their inoperative position and out of engagement with the wheel. To insure these dogs being held in their inoperative position and remove any possibility of their coming 15 in contact with the wheel during the running of the motor, holes 28 are provided in the arm of the dogs which register with similar holes 29 in the bell-cranks, and a locking pin or bolt is inserted in these holes so as to secure 20 the dogs in position out of contact with the wheel and prevent any movement of the dogs.

In the operation of the apparatus, the locking pins are first removed from the holes 25 28 and 29 in the bell-cranks and dogs. The dogs 21 and 22 are then turned into the position shown by full lines in the drawing, the fingers 24^a and 25^a on the dogs being yieldingly held in contact with the face of the 30 wheel 2 by the counterweights. The valve controlling the supply of fluid pressure to the cylinder 5 is then manipulated by the operator so as to admit fluid pressure into one end or the other of the cylinder and reciprocate 35 the piston 6, this movement of the piston reciprocating the cross head on the slide 20 so as to rock the bell-cranks 11 and 12 on the pins or shafts 9. As the piston moves toward the stuffing box end of the cylinder 40 from the central position shown, the wheel 2 is moved in the direction of the arrow and when the piston 6 has reached the end of its stroke, the finger 25^a on the dog 22 will have engaged with the adjacent barring notch in 45 the face of the wheel. The valve operating mechanism is then moved to cause the piston to travel in the opposite direction when the dog 22 will be moved upwardly and by reason of the engagement of its finger 25^a with 50 the barring notch will move the wheel another step forward in the direction of the arrow. When the dog 22 is being advanced upwardly, the dog 21 will be moved in the opposite direction and by the time the dog 22 has 55 been moved to the full extent of its stroke, the finger 24^a on the dog 21 will have engaged with another of the barring notches in the periphery of the wheel. The above operations are repeated as often as is necessary 60 to move the engine throughout the desired part of a revolution or the desired number of revolutions, should such occasion arise.

When it is desired to move the engine or motor in a direction opposite to that indicated by the arrow, the dogs 21 and 22 are

swung about the axis of the shafts 23 so as to extend in a direction shown by dotted lines, the counterweight 27 in this case also yieldingly holding the dogs in engagement with the face of the wheel. When the dogs are in 70 this position, the fingers 24 and 15 on the dogs 21 and 22 are in engagement with the wheel and enter the successive barring notches 3 when the bell cranks are actuated by means of the piston 6 and fluid pressure cylinder 5 and gradually turn the wheel in the opposite direction to that indicated by 75 the arrow.

The advantages of our invention will be apparent to those skilled in the art. The engine is moved positively through a part of a revolution by each forward or backward stroke of the piston, and the wheel is held in its moved position after the completion of each step by step movement. The wheel 85 can be turned in either direction to any extent that may be desired.

The apparatus is simple and is easily kept in repair.

Another advantage of the invention is that 90 the apparatus may be used to turn the fly wheel or driving pulley of a rolling mill motor so as to slacken the coupling boxes on the wabblers of the rolls and the connecting spindles, and the motor can be moved to 95 such an extent and with such ease that this apparatus can be employed, instead of wasting a large amount of time usually necessary in performing this operation, by means of the motive power of the motor.

It will be understood that we do not limit 100 our invention to reciprocating engines having fly wheels, as it is equally applicable to motors having belt pulleys or sheave wheels.

Modifications in the construction and arrangement of the parts may be made. Instead of having a double arrangement of dogs and bell-cranks, a single dog may be employed which would require but a single bell-crank. The apparatus may be constructed to move the motor in one direction and many other changes may be made without departing from our invention.

We claim:—

1. Apparatus for starting motors having a 115 wheel comprising a dog arranged to swing into and out of engagement with barring notches in the rim of the wheel, and fluid pressure means connected to the dog and adapted to actuate the dog to rotate the 120 wheel; substantially as described.

2. Apparatus for starting motors having a wheel comprising a dog arranged to swing into and out of engagement with barring notches in the rim of the wheel, and having a 125 counterweight for holding the dog in contact with the wheel, and fluid pressure means arranged to actuate the dog and rotate the wheel; substantially as described.

3. Apparatus for starting motors having a 130

wheel comprising dogs arranged to swing into and out of engagement with barring notches in the rim of the wheel and fluid pressure means connected to said dogs, and adapted 5 to actuate the dogs to rotate the wheel; substantially as described.

4. Apparatus for starting motors having a wheel comprising dogs arranged to swing into and out of engagement with barring 10 notches in the rim of the wheel, counterweights arranged to hold the dogs in contact with the wheel and fluid pressure means arranged to actuate the dogs and rotate the wheel; substantially as described.

15 5. Apparatus for starting motors having a wheel comprising swinging dogs arranged to be moved into engagement with barring notches in the rim of the wheel and oppositely projecting fingers on the end of the 20 dogs, and fluid pressure means connected to the dogs and adapted to actuate the dogs to rotate the wheel in either direction, the fingers on one side of said dogs adapted to engage with and move the wheel in one direction, the opposite fingers engaging with and moving the wheel in the opposite direction; substantially as described.

6. Apparatus for starting motors having a wheel comprising a frame, a bell-crank pivotally mounted thereon, a swinging dog pivotally mounted on the bell-crank, and arranged to be swung into and out of engagement with barring notches in the rim of the 30 wheel, and means for rocking the bell-crank 35 to move the dog and rotate the wheel; substantially as described.

7. Apparatus for starting motors having a wheel comprising a frame, bell-cranks pivotally mounted thereon, swinging dogs pivotally mounted on the bell-cranks, and arranged to contact with barring notches in the rim of the wheel and fluid pressure means for rocking the bell-cranks to move the dogs and partly rotate the wheel, the dogs being arranged to alternately move the wheel; substantially as described.

8. Apparatus for starting motors having a wheel comprising a frame, bell-cranks pivotally mounted thereon, a swinging dog pivotally mounted on an arm of each bell crank and arranged to engage with barring notches in the rim of the wheel, a reciprocating cross head having sliding engagement with the other arms of said bell-cranks, and fluid 50 pressure means for actuating said cross-head to rock the bell-cranks and rotate the wheel; substantially as described.

9. Apparatus for starting motors having a wheel comprising a frame, bell-cranks pivotally mounted thereon, a dog pivotally mounted on the arm of each of the bell-cranks and extending forwardly into contact with the rim of the wheel, a counterweight connected 60 with the dogs arranged to yieldingly hold

said dogs in contact with the wheel, a cross-head mounted on the frame arranged to reciprocate thereon having sliding connections with one arm of each bell-crank, a fluid pressure cylinder mounted on the frame having a piston and piston rod connected to said cross-head, and arranged to actuate the cross-head to move said dogs; substantially as described.

10. Apparatus for starting motors having a wheel comprising a dog arranged to swing 75 into and out of engagement with barring notches in the rim of the wheel, and a motor connected to and arranged to actuate the dog to rotate the wheel; substantially as described.

11. Apparatus for starting motors having a wheel comprising a dog arranged to swing into and out of engagement with barring notches in the rim of the wheel, means for holding the dog in contact with the wheel 85 and means connected with the dog and arranged to actuate the dog to rotate the wheel; substantially as described.

12. Apparatus for starting motors comprising a pair of pushing dogs, a motive device and connections between the motive device and dogs for causing the latter to alternately engage and move the motor through a part of a revolution when said motive device is actuated; substantially as described.

13. Apparatus for starting motors having a wheel comprising a pair of pushing dogs, a motive device, and connections between the motive device and the dogs for causing the latter to alternately engage with and actuate 100 the wheel, one of the dogs engaging the wheel when the other is disengaged; substantially as described.

14. Apparatus for starting motors having a wheel comprising a pair of pushing dogs, a 105 motive device, and connections between the motive device and the dogs for causing the latter to alternately engage with and actuate the wheel, and means for holding the dogs out of operative position; substantially as 110 described.

15. Apparatus for starting motors having a wheel comprising a pair of pushing dogs, a motive device and connections between the motive device and the dogs for causing the 115 dogs to be rocked in opposite directions when the motive device is operated; substantially as described.

16. Apparatus for starting motors having a wheel comprising a pair of pushing dogs, a 120 motive device, and connections between the motive device and the dogs for causing the latter to alternately engage and actuate the wheel, the dogs being reversible to change the direction of their action on the wheel; 125 substantially as described.

17. The combination with a fly-wheel provided with a series of barring notches for the

rim of the wheel, of a dog arranged to swing into and out of engagement with the notches and fluid pressure means connected to the dog and adapted to actuate the dog to move 5 the fly-wheel.

18. The combination with a fly-wheel provided with barring notches in its rim, of a dog arranged to swing into and out of engagement with the notches and a motor con-

nected to and arranged to actuate the dog to 10 move the wheel.

In testimony whereof, we have hereunto set our hands.

SYDNEY DILLON.
JOHN RICHARDSON.
